(57) **CLAIM**

The ornamental design for an expandable and removable mattress encasement, as shown and described.

DESCRIPTION

FIG. 1 is a perspective view of an expandable and removable mattress encasement, showing my new design;

FIG. 2 is an exploded perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, showing the expandable and removable mattress encasement being retracted;

FIG. 10 is a partially enlarged view of the area labeled 10 in FIG. 2, showing design of a buckle in the expandable and removable mattress encasement;

FIG. 11 is another partially enlarged view of the area labeled 11 in FIG. 2, showing a zipper design in the expandable and removable mattress encasement;

FIG. 12 is another partially enlarged view of the area labeled 12 in FIG. 1; and,

FIG. 13 is another partially enlarged view of the area labeled 13 in FIG. 1.

The zipper pull shown in broken lines in the figures represents environment and forms no part of the claimed design. The long broken lines in the figures show stitching, and form no part of the claimed design. The dash-dot broken lines are to show enlarged areas and form no part of the claimed design.
